UNITED STATES PATENT OFFICE.

MURRELL O. CLARK, OF VERONA, MISSISSIPPI.

WAGON-UNLOADING MECHANISM.

SPECIFICATION forming part of Letters Patent No. 752,519, dated February 16, 1904.

Application filed July 11, 1903. Serial No. 165,131. (No model.)

To all whom it may concern:

Be it known that I, MURRELL O. CLARK, a citizen of the United States, residing at Verona, in the county of Lee and State of Mississippi, have invented new and useful Improvements in Wagon-Unloading Mechanism, of which the following is a specification.

My invention relates to new and useful improvements in mechanism for unloading wagons; and its object is to provide apparatus which can be readily installed within a barn or other structure and whereby one person can, with the assistance of the horses belonging to the vehicle, unload material from the wagon, convey it to a desired point within the barn, deposit it, and return the wagon-body to its initial position.

A further object is to provide means for readily securing a wagon-body to the unloader.

Another object is to employ novel means for suspending the wagon-body during its transportation within the barn.

Further objects are to provide means for automatically dumping the wagon-body and for raising it to a horizontal position prior to its return to its normal position upon the running-gear of the vehicle.

With the above and other objects in view 30 the invention consists in the novel construction and combination of parts hereinafter more fully described and claimed, and illustrated in the accompanying drawings, showing the preferred form of my invention, and in which—

Figure 1 is an end elevation of the apparatus within a barn. Fig. 2 is a plan view thereof. Fig. 3 is a longitudinal section on line 3-3, Fig. 1, and showing the positions of the parts prior to hoisting a wagon-body. Fig.

4 is a side elevation of a wagon-body suspended from one of the carriages of the apparatus, and Fig. 5 is a bottom plan view of a portion of the wagon-body-engaging mechanism and showing in dotted lines position 45 the holding-bar may assume.

Referring to the figures by numerals of reference, 11 are the joists of a barn or other structure 2, and these joists are cut away longitudinally, as shown at 3, to permit strips 4

to be secured to the ends of the recessed portions. These strips have arms 5, extending inwardly from the edges and forming supports for tracks 6, secured thereto. Between each pair of tracks 6 are mounted two grooved rollers 7, journaled at the sides of a frame 8, constructed of suitably-arranged beams and forming a car. Two pair of grooved rollers 9 are also mounted between the tracks 6 and are arranged to the sides of a second car 10. Journaled in this car near each corner is a pulley 11, and over each pulley extends a cable 12, which is also mounted on a pulley 13, arranged near one corner of the car 8. These cables may be fastened to the car 8 in any desired manner. To the lower ends of the cables 12 is fastened 65 a preferably rectangular frame 14, having forked ears 15 at one end thereof, in which are pivoted rods 16. A rod 17 is arranged under and longitudinally of the opposite end of the frame 14, and the ends of this rod are 70 fastened to L-shaped arms 18, pivoted to the sides of the frame and extending laterally therefrom. Loops 19 are arranged at the centers of the sides of frame 14 and are adapted to come in contact with and automatically engage hooks 20, pivoted to the sides of car 10 and having arms 21 projecting upwardly therefrom.

The rods 16 are adjustably secured in sleeves 22, arranged on a rod 23, and loosely mounted 80 on this rod are sleeves 24, having hooked rods 25 adjustably fastened therein. Sleeves 26 are also loosely arranged on the rod 23 and have forked ears 27, in which are pivoted holding-bars 28. Into these bars project and 85 are adjustably secured strips 29, having cam-shaped heads 30, forming hooks 31, which normally engage the rod 17.

Trips 32 are adjustably secured to the tracks 6 in any suitable manner and project into the 90 paths of the arms 18. Stops 33 are arranged upon the inner faces of the tracks and project into the paths of the arms 21 of hooks 20. These stops are preferably arranged directly above a point to which wagons to be 95 unloaded are brought. Pulleys 34 are located at different points in the structure 2, and arranged upon them is a cable 35, which is fas-

tened to the front of the car or carriage 8 and extends downward to a point near the wagon to be unloaded. A cable 36 is mounted on pulleys 37 on carriage or car 10 and has a hook 38 at one end, while the other end is adapted to be held by the operator.

The operation of the device is as follows: A loaded wagon is driven to a point under the carriage 10 and strips 29 detached from rod 17. The holding-bars 28 are then swung under the ends of the wagon-body 39 and the hooks 31 placed in engagement with the rod 17. Rods 25 are hooked to the wagon-body 39 and locked in sleeves 24 by set-screws 40 or other suitable devices. Hook 38 is secured to the side of the body 39. The horse or horses of the wagon or a special team provided for the purpose is then hitched to the cable 35 and driven forward. Longitudinal movement of the car 8 will thus be produced, and the cables 12 fastened thereto will draw upward the frame 14 and the wagon-body 39 connected thereto. The carriage 10 is held against longitudinal movement during the hoisting of the frame 14 and the wagon-body by one or more persons grasping the cable 36 and drawing downward thereupon. The loops 19 will, as is obvious, automatically engage hooks 20. When the frame 14 reaches the limit of its upward movement, car 10 is drawn forward after car 8 until arms 18 come into contact with the trips 32. These trips will cause the arms to swing rod 17 from under hooks 31, and strips 29 and bars 28 will therefore swing downward and carry the body 39 therewith. This body is prevented from becoming displaced by the rods 25. The material carried by the wagon-body will thus be discharged. The horses can then be attached to cable 36 and when driven forward will first draw the bars 28 and strip 29 upward, causing the hooks 31 to reengage the rod 17. The two carriages 8 and 10 are then drawn backward until the arms 21 contact with stops 33, when hooks 20 will be automatically removed from loops 19, and the wagon-body 39 and its holding-frame can then be lowered into proper position. Any suitable supporting means may be substituted for the hooks 20, and I do not desire to be understood as limiting myself to the specific construction and arrangement described and shown. It will be seen that the apparatus is very simple and effective and by its use one person can, unassisted, unload wagons at desired points.

In the foregoing description I have shown the preferred form of my invention; but I do not limit myself thereto, as I am aware that modifications may be made therein without departing from the spirit or sacrificing any of the advantages thereof, and I therefore reserve the right to make such changes as fairly fall within the scope of my invention.

Having thus described the invention, what is claimed as new is—

1. In a wagon - unloading apparatus, the combination with a track, a car thereon, and means for propelling the car; of a second car upon the track, cables loosely mounted on said car and secured to the first-mentioned car, a frame secured to the cables, wagon-body-supporting means pivotally connected thereto, and means for locking the same in supporting position.

2. In a wagon - unloading apparatus, the combination with a track, a car thereon, and means for propelling the car; of a second car upon the track, cables loosely mounted on said car and secured to the first-mentioned car, a frame secured to the cables, a rod connected thereto, wagon-body-supporting bars pivoted on the rod, and means for locking the bars in supporting position.

3. In a wagon - unloading apparatus, the combination with a track, a car thereon, and means for propelling the car; of a second car upon the track, cables loosely mounted on said car and secured to the first-mentioned car, a frame secured to the cables, a rod connected thereto, wagon-body-supporting bars pivoted to the rod, hooked strips connected to the bars, and a movable rod upon the frame and normally engaged by the hooked strips.

4. In a wagon - unloading apparatus, the combination with a track, a car thereon, and means for propelling the car; of a second car upon the track, cables loosely mounted on said car and secured to the first-mentioned car, a frame secured to the cables, a rod connected thereto, wagon-body-supporting bars pivoted to the rod, hooked strips extending from the bars, arms pivoted to the frame, a rod connecting said arms and normally engaged by the hooked strips, and means for automatically releasing the rod from the strips.

5. In a wagon - unloading apparatus, the combination with a track, a car thereon, and means for propelling the car; of a second car upon the track, cables loosely mounted on said car and secured to the first-mentioned car, a frame secured to the cables, a rod suspended therefrom, wagon-body-supporting bars pivotally connected to the rod, hooked wagon-body-engaging rods adjustably secured to the said rod, hooked strips extending from the bars, arms pivoted to the frame, a rod connecting the arms and normally engaged by the hooked strips, and means for automatically releasing the rod from said strips.

In testimony whereof I affix my signature in presence of two witnesses.

MURRELL O. CLARK.
